HOLDER FOR SELECTIVELY SUSPENDING
A HAMMOCK

Edward W. Anderegg, West De Pere, Wis.

Application September 15, 1950, Serial No. 185,129

4 Claims. (Cl. 5—127)

1

This invention relates to hammock supports, and more particularly to a holder for selectively suspending a hammock on either a relatively non-tiltable or swinging support.

An object of this invention is to provide a holder for selectively suspending a hammock on either a relatively non-tiltable support usually preferred by adults, or a swinging support usually preferred by children.

Another object of this invention is to construct a holder which can be used to selectively suspend the head end of a hammock at one point to thereby provide a two-point rocking support in cooperation with the supported foot end of the hammock or at two points to thereby provide a three-point relatively non-tiltable support in cooperation with the supported foot end of the hammock.

A further object of this invention is to provide a hammock holder which is relatively simple in structure, cheap to manufacture, and easy to attach to a hammock and hammock stand.

The above and still further objects and advantages of the invention will become apparent upon consideration of the following detailed description of the invention when taken in conjunction with the accompanying drawings, wherein:

Figure 1 is a perspective view showing the hammock holder of the present invention supported between the head end of a hammock and the head-supporting bar of the hammock stand;

Figure 2 is a fragmentary top plan view of the hammock holder of the present invention, showing the holder supporting the head end of a hammock at two spaced points;

Figure 3 is a longitudinal view, partially in section, of the supporting rod forming a part of the hammock holder of the present invention;

Figure 4 is an enlarged fragmentary perspective view of the supporting rod shown in Figure 3;

Figure 5 is a fragmentary top plan view of the hammock holder of the present invention, shown supporting the head end of the hammock at one point; and

Figure 6 is an enlarged fragmentary sectional view taken along the line 6—6 of Figure 5.

Referring now more particularly to the drawings, wherein like reference numerals have been used throughout the several views to designate like parts, there is shown the hammock holder of the present invention, generally designated by the reference numeral 10 connected to a hammock stand 11 and suspendingly supporting the head end of a hammock 12. The hammock stand

2

11 forms no part of the present invention and embodies a pair of convergent legs 13, 14 which have their convergent ends secured together and cooperating to support the foot end 15 of the hammock 12 at a single point. The hammock stand 11 further embodies a pair of spaced, upwardly inclined legs 16, 17 which have their upper ends connected together by a horizontally disposed head-supporting bar 18 which carries at least three spaced hooks, designated generally by the reference numerals 19, 20 and 21.

The holder 10 comprises a supporting rod 25 which is adapted to be arranged in spaced, parallel relation with respect to the head-supporting bar 18 of the hammock stand 11 contiguous to and spaced from the head end 22 of the hammock 12. Contiguous to each of its ends, the supporting rod 25 is provided with transversely extending slots 26, 27.

20 Arranged transversely of and intermediate the ends of the rod 25 are two spaced, triangularly-shaped bails 28, 29, each mounted in the adjacent one of the slots 26, 27 for back-and-forth movement transversely of the rod 25.

25 Suitable means are carried by the rod 25 and engage each of the bails 28, 29 for limiting the back-and-forth movement thereof. As clearly illustrated in Figure 6, the means embodies a pin 30 secured transversely of each end of the rod 25 intermediate the ends of the adjacent one of the slots and passing through the adjacent one of the bails. Similarly, a second pin 31 is provided intermediate the ends of the slot 27, the pin 31 engaging the bail 29 for limiting the movement thereof.

35 Supported on the end of each of the bails 28, 29 remote from the head-supporting bar 18, are the flexible suspension means 32, 33 which are adapted to be secured to the head end 22 of the hammock 12. As clearly illustrated in the several views of the drawings, the suspension means 32, 33 embodies a plurality of flexible cords secured at spaced intervals along the head-end 22 of the hammock 12 and converging for securing to the adjacent end of the bails 28, 29.

40 Carried by the rod 25 intermediate and spaced from the bails 28, 29 is an embracing element, generally designated by the reference numeral 35, which is adapted to be secured to the hook 20 carried by the head-supporting bar 18 to thereby provide a one-point support for the head end of the hammock 12. The embracing element 35 embodies an elongated bolt 36 having one end extending transversely through the opposed apertures 37, 38 provided midway between the ends

of the rod 25 and has the other end shaped into an eyelet 39. The securement of the embracing element 35 to the rod 25 is effected by means of the spaced washers 40, 41 and the nuts 42, 43 engaging the adjacent one of the washers to thereby urge the washers into abutting and frictional engagement with the outer periphery of the rod 25.

When it is desired to use the holder 10 of the present invention for selectively suspending the hammock on a relatively non-tiltable support usually preferred by adults, the end of each of the bails 28, 29 contiguous to the head-supporting bar 18 are attached to the adjacent hooks 19, 21 carried by the latter. Thus, the head end 22 of the hammock 12 is supported at two spaced points and in cooperation with the supported foot end 15 of the hammock 12 provide a relatively non-tiltable, three-point support for the hammock 12.

When it is desired to use the holder 10 for suspendingly supporting a hammock on a support usually preferred by children, the eye 39 of the embracing element 35 is engaged over the hook 20 carried midway between the ends of the head-supporting bar 18. Thus, the head end of the hammock 12 is supported at a single point which, in cooperation with the supported foot end of the hammock, provides a two-point rocking support for the hammock 12. The two-point support for the head end of the hammock is clearly illustrated in Figure 2, while the one-point support for the head end of the hammock is clearly illustrated in Figure 5.

Although one embodiment of the hammock holder of the present invention has been described, it is readily apparent that numerous modifications can be made without departing from the spirit of the invention as set forth in the appended claims.

What I claim is:

1. A holder for suspendingly supporting the head end of a hammock from the head-supporting bar of the hammock stand comprising a supporting rod adapted to be arranged in spaced parallel relation with respect to said head-supporting bar, at least two spaced bails arranged transversely of and intermediate the ends of said rod and each mounted on the latter for back-and-forth movement transversely of said rod, means carried by said rod and engaging each of said bails for limiting the back-and-forth movement thereof, flexible suspension means supported on the end of each of said bails remote from said head-supporting bar and adapted to be secured to said head end of said hammock, and embracing means on said rod intermediate and spaced from said bails and adapted to be secured to a hook carried by said head-supporting bar to thereby provide a one-point support for the head end of said hammock.

2. A holder for suspendingly supporting the head end of a hammock from the head-supporting bar of a hammock stand comprising a supporting rod adapted to be arranged in spaced parallel relation with respect to said head-supporting bar, at least two spaced bails arranged transversely of and intermediate the ends of said rod and each mounted on the latter for back-and-forth movement transversely of said rod, means

carried by said rod and engaging each of said bails for limiting the back-and-forth movement thereof, flexible suspension means supported on the end of each of said bails remote from said head-supporting bar and adapted to be secured to said head end of said hammock, embracing means on said rod intermediate and spaced from said bails and adapted to be secured to a hook carried by said head-supporting bar to thereby provide a one-point support for the head end of said hammock, and the end of each of said bails contiguous to said head-supporting bar being adapted to be attached to an adjacent hook carried by the latter to thereby provide a two-point support for the head end of said hammock.

3. A holder for suspendingly supporting the head end of a hammock from the head-supporting bar of a hammock stand comprising a supporting rod adapted to be arranged in spaced parallel relation with respect to said head-supporting bar, at least two spaced bails arranged transversely of and intermediate the ends of said rod and each mounted on the latter for back-and-forth movement transversely of said rod, means carried by said rod and engaging each of said bails for limiting the back-and-forth movement thereof, and flexible suspension means supported on the end of each of said bails remote from said head-supporting bar and adapted to be secured to said head end of said hammock, the end of each of said bails contiguous to said head-supporting bar being adapted to be attached to an adjacent hook carried by the latter to thereby provide a two-point support for the head end of said hammock.

4. A holder for suspendingly supporting the head end of a hammock from the head-supporting bar of a hammock stand comprising a supporting rod adapted to be arranged in spaced parallel relation with respect to said head-supporting bar, at least two spaced bails arranged transversely of and intermediate the ends of said rod and each mounted on the latter for back-and-forth movement transversely of said rod, a pin secured transversely of each end of said rod and passing through the adjacent one of said bails for limiting the back-and-forth movement thereof, flexible suspension means supported on the end of each of said bails remote from said head-supporting bar and adapted to be secured to said head end of said hammock, and embracing means on said rod intermediate and spaced from said bails and adapted to be secured to a hook carried by said head-supporting bar to thereby provide a one-point support for the head end of said hammock.
